Primary Examiner — Catherine S Posthauer*(74) Attorney, Agent, or Firm* — Nixon Peabody LLP(57) **CLAIM**

The ornamental design for a closure with tamper-evident band as shown and described.

DESCRIPTION

FIG. 1 is a top perspective view of a closure, showing our new design.

FIG. 2 is a front view of the closure of FIG. 1.

FIG. 3 is a back view of the closure of FIG. 1.

FIG. 4 is a top view of the closure of FIG. 1.

FIG. 5 is a bottom view of the closure of FIG. 1.

FIG. 6 is a bottom perspective view of front side of the closure of FIG. 1; and,

FIG. 7 is a bottom perspective view of the back side of the closure of FIG. 1.

The broken lines are shown for the purpose of illustrating parts of the article that form no part of the claim.
